TYPEWRITING AND LIKE MACHINE

James H. Rand, Jr., Buffalo, N. Y., assignor to
Remington Rand Inc., Buffalo, N. Y., a corpora-
tion of Delaware

Application March 8, 1932, Serial No. 597,504

8 Claims. (Cl. 197—180)

My invention relates to typewriting, computing and like machines, and the object of the invention is to provide a protecting shield through which the operator may have a clear vision of the writing being produced on the machine and which affords a protection to the operator's eyes against the glare or reflection of light from the work sheet.

A further object of my invention is to provide 10 a shield or device of the character referred to which is in the nature of an attachment that may be readily applied to different makes of typewriting, computing and like machines.

A still further object of my invention is to 15 provide a shield of the character specified that is so mounted on the carriage of a typewriting, computing or like machine that it may be readily shifted from its normal position of use to an ineffective unobstructing position where it gives 20 ready access to the work sheet for making erasures, etc.

To the above and other ends which will hereinafter appear, my invention consists in the features of construction, arrangements of parts 25 and combinations of devices set forth in the following description and particularly pointed out in the appended claims.

In the accompanying drawings wherein like reference characters indicate corresponding 30 parts in the different views—

Fig. 1 is a detail, fragmentary, side view of the upper portion of a Remington typewriting machine equipped with a shield of my invention, the shield being shown in position for use;

35 Fig. 2 is an enlarged, detail, fragmentary, fore and aft, sectional view of the same, the section being taken on the line 2—2 of Fig. 3 and looking in the direction of the arrows at said line;

Fig. 3 is a front view of the construction with 40 parts in section, the section being taken on the line 3—3 of Fig. 1 and looking in the direction of the arrows at said line;

Fig. 4 is an enlarged, detail, longitudinal, sectional view of the pivotal mounting at one end 45 of the shield;

Fig. 5 is a transverse, sectional view of the same taken on the line 5—5 of Fig. 4;

Fig. 6 is a view corresponding to Fig. 1 of a modified form of shield shown applied to a 50 No. 6 Remington noiseless typewriting machine;

Fig. 7 is a transverse, sectional view of the same taken on the line 7—7 of Fig. 8 and looking in the direction of the arrows at said line;

Fig. 8 is a detail, front view of the construction shown in Figs. 6 and 7; and

Fig. 9 is an enlarged, detail, sectional view of the pivotal connection at one end of the shield illustrated in Figs. 6, 7 and 8.

In operating typewriting and combined typewriting and computing machines and the like, the operator keeps her eyes more or less constantly on the work sheet at the printing line. This is a steady strain on the eyes and the glare or reflection from the white work sheet in the machine adds to the eye strain and is annoying to the operator. By my present invention I provide a shield of glass, mica, celluloid, or some such suitably transparent material colored or suitably tinted (an amber tint for example) and through which the operator may clearly see the typewriting. This relieves the strain on the eyes and prevents the reflection of the strong light rays from the work to the eyes of the operator.

This shield, which preferably is substantially coextensive with the length of the platen, I mount on the machine, and preferably on the carriage thereof, so as to be held interposed between the eyes of the operator and the work sheet and in her line of vision of the typewritten matter, so that the latter may be seen by the operator through the shield. By mounting the shield on the carriage it travels therewith and with the work sheet so that there is no relative movement between the two in the travel of the carriage to annoy the operator and detract her attention from the typing operations.

In Figs. 1 to 5 inclusive I have shown one form of construction in which the shield is shown mounted on the carriage of a standard Remington typewriting machine. In this form of construction an amber tinted, non-shatterable glass shield 1 is received at its lower corners in sheet metal pockets or carriers 2 in which the shield is received with a tight fit that holds the shield connected to the pockets. Each pocket 90 embraces the shield on one corner at the front and rear faces thereof and at an outer edge. Each so-called pocket 2 is formed from sheet metal with a rounded lower end 3 that surrounds one end portion of a supporting shaft or spindle 4; the shaft at its ends extending beyond the pockets through openings therein. Each pocket 2 is fixedly attached to the shaft 95 4 by spot welding it thereto, thus forming a rigid frame of the end pockets 2 and shaft 4 for supporting the glass shield on and connecting it to the carriage of a typewriting and like machine.

As indicated in Fig. 4 each end of the shaft 4 is recessed at 5 to receive a coiled spring 6. 116

One end of each spring 6 is seated in an opening in a block 7 that is secured with a drive fit in the bottom of its recess 5. In this manner each spring 6 is fastened at one end to the shaft 4 and tends to turn it, whereas the other end of each spring is anchored by passing into a longitudinal slot 8 in a fixedly held headed pivot pin 9. Each pivot pin passes through a bearing opening in a bracket 10 or 10^a and is received in the associated recess 5 in one end of the shaft to provide a pivotal support on which the shaft turns. Each pivot pin 9 is secured in place by a headed screw 11 that is received in a tapped opening in the associated supporting bracket 10 or 10^a and the head of screw 11 overlaps the head of the companion pivot pin 9 and secures the latter firmly connected to the associated bracket.

By these means the springs 6 tend to turn the shaft and move the shield to the effective position shown in Fig. 1 where the shield is maintained in line of the operator's vision of the printing line and the written matter on the work sheet 12 as the latter is fed forward by the platen 13.

In order to limit the movement of a shield to effective position under the action of the springs 6, I provide a suitable stop 14. In the present instance this stop is formed as a projection on the right-hand supporting bracket 10^a and extends into the path of the right-hand pocket or carrier 2 and limits the forward movement thereof and of the shield.

The supporting brackets by which the shield is attached to the machine may be of any suitable construction depending somewhat on the particular machine to which the shield is to be attached.

In the Figs. 1 to 5 construction each of the supporting brackets 10, 10^a is provided with a foot piece 15 that is pierced to receive the stem of a headed screw 16, which is one of the usual screws employed in the Remington standard machines to secure parts to the front cross bar 17 of the carriage 18. The screws 16 usually employed for other purposes are also made available in the present instance to secure the supporting brackets 10 and 10^a to the carriage. The hole in the foot piece 15 in the right-hand bracket 10^a is elongated, as shown in Fig. 3, to provide a slight relative adjustment between the brackets in order that the shields may be readily placed on different machines having the screws 16 in slightly different positions thereon. I also prefer to secure the right-hand supporting bracket 10^a in place with the aid of a clamping plate 18^a interposed between the head of the associated screw 16 and foot piece of the bracket, to provide a secure hold on the bracket and prevent the slotted foot piece from spreading.

In the construction shown in Figs. 6 to 9 inclusive the shield 1^a is made of transparent celluloid, mica, or similar material tinted as previously described. The frame by which the shield is supported in this form of the construction includes an inverted U-shaped sheet metal frame that embraces the shield on three of its edges and is riveted at 19 to the intervening shield. A tubular sheet metal member 4^a constitutes a rock shaft by which the shield is supported for pivotal movement as previously described. This tubular member 4^a has upwardly projecting flanges 20 throughout the length thereof which embrace the shield 1^a on opposite

sides thereof and are riveted thereto and to each other at 21.

The shield supporting frame comprising the tubular member 4^a, 20 and 2^a is pivoted to supporting brackets 22 substantially as hereinbefore described in connection with the form of construction shown in Figs. 1 to 5 inclusive. Thus, each headed pivot pin 23 receives a bearing in the associated supporting bracket 24 and is received in one end of the tubular member 4^a and is held in place by a clamping screw 25 threaded into the companion supporting bracket. Each pivot pin 23 is grooved at 26 to receive and provide an anchorage for the companion coiled spring 27 at one end thereof, the other end of each spring being connected to a block 28 held by a drive fit in the tubular member 4^a. Each bracket 24 has an upwardly directed extension 29 that constitutes a stop with which a side arm of the member 2^a of the shield-carrying-frame coacts to limit the forward movement of the frame under the action of the springs 27.

It will be seen that the supporting brackets 24 in this form of construction are of different formation from the brackets 10 and 10^a previously described due to the fact that the brackets 24 are intended for attachment to the usual arms 30 of the carriage of a No. 6 Remington noiseless machine. At its attaching end 24^a each bracket 24 is made substantially U-shaped in cross section. This enables each bracket to embrace the edges of the companion arm 30 of the carriage and to be fixedly secured thereto by a companion pivot screw 31 usually employed for mounting the paper bail, a nut 32 coacting with each screw 31 to hold the companion bracket in place.

It will be understood that in each of the constructions described, the shield and its supporting brackets may be readily attached as a unit to a typewriting machine by means existing in the machine and without modifying the structural features thereof.

One of the main objects of mounting each of the shields so that it may be readily moved to an ineffective position, and in providing spring means to enable the shield to be automatically restored to effective position when released, is to facilitate making erasures at or near the front and top of the platen while the work sheet or sheets remain in the machine. In reaching back to make an erasure the operator's arms come into contact with the shield and move it down to an unobstructing position where it gives free access to the work sheet. While making such erasure the operator's arms remain on the shield and hold it down. When the erasure is made the spring for the shield return it to normal effective position when the operator's arms are withdrawn from contact therewith.

From the foregoing description it will be seen that I have provided a simple, effective, and comparatively inexpensive shield that relieves the strain on the operator's eyes and may be readily applied as an attachment to typewriting and like machines, and one that is automatically displaced to an ineffective and unobstructing position in the act of making erasures and is automatically returned to effective position after the erasure has been made.

Various changes may be made in the construction, and features thereof may be employed without others, without departing from my invention as it is defined in the accompanying claims.

- What I claim as new and desire to secure by Letters Patent is:
1. In a typewriting or like machine, the combination of a platen that travels in the direction of its length, a tinted transparent shield through which the operator may view the writing on a work sheet in the machine in any position that the platen may assume in its travel, and means for supporting said shield on the machine to travel with the platen and interposed in the line of vision of the operator when inspecting the written matter on a work sheet carried by the platen, said supporting means including means that enable said shield to be shifted backward from the effective position of use to an unobstructing position by the operator in reaching back to make an erasure on the work sheet supported on the platen. 80
  2. In a typewriting or like machine, the combination of a platen, a tinted transparent shield through which the operator may view the writing on a work sheet in the machine, and means for supporting said shield on the machine forwardly of said platen interposed in the line of vision of the operator when inspecting the written matter on a work sheet carried by the platen, said supporting means including means that enable the shield to be shifted backward to an unobstructing position intermediate said supporting means and said platen by the operator in reaching back to make an erasure on the work sheet supported on the platen. 85
  3. In a typewriting or like machine, the combination of a platen, a tinted transparent shield through which the operator may view the writing on a work sheet in the machine, and means for supporting said shield on the machine interposed in the line of vision of the operator when inspecting the written matter on a work sheet carried by the platen, said supporting means including means that enable the shield to be shifted to an unobstructing position by the operator in reaching back to make an erasure on the work sheet supported on the platen and to be automatically returned to normal effective position when the operator's hands are withdrawn from the work sheet. 90
  4. In a typewriting or like machine, the combination of a carriage, a tinted transparent shield through which the operator may view the writing on a work sheet carried by the carriage, and means for supporting said shield on the carriage to travel therewith and in a position where it is arranged in the line of vision of the operator when inspecting writing on a work sheet carried by the carriage irrespective of the position of the carriage in its line of travel, said supporting means including means that enable said shield to be deflected from and to be spring-returned to effective position. 95
  5. In a typewriting or like machine, the combination of a carriage, a tinted transparent shield through which the operator may view the writing on a work sheet carried by the carriage, brackets detachably connected to the carriage and on which said shield is pivoted for movement from effective position for use to an unobstructing position, and spring means which tend to maintain said shield in and return it to effective position. 100
  6. In a typewriting or like machine the combination of a carriage, a tinted transparent shield through which the operator may view the writing on a work sheet carried by the carriage, a sheet metal frame or carrier by which said shield is carried, said frame or carrier comprising a rock shaft and means fixedly connected therewith for holding the shield on said shaft, brackets detachably connected to the carriage, pivotal connections for supporting said frame on said brackets, and spring means for turning said rock shaft. 105
  7. In a typewriting or like machine, the combination of a carriage, a tinted transparent shield through which the operator may view the writing on a work sheet carried by the carriage, a sheet metal frame or carrier by which said shield is carried, said frame or carrier comprising a rock shaft and means fixedly connected therewith for engaging said shield at edge portions thereof and thus connecting the shield to said shaft, detachable means for pivotally supporting said rock shaft on the carriage, a stop for limiting the pivotal movement of the frame or carrier in one direction, and spring means 110 which tend to maintain said frame against said stop. 115
  8. In a typewriting machine, the combination of a platen, a tinted transparent shield through which the operator may view the writing on the work sheet in the machine and the operator's eyes will be protected against the reflection of light from the work sheet, and means that enable said shield to be displaced from effective position as the operator reaches back to make an erasure and to be automatically returned to effective position when the hands of the operator are withdrawn from the work sheet. 120
